INVENTOR

UNITED STATES PATENT OFFICE.

WILLIAM P. ABENDROTH, OF PORT CHESTER, NEW YORK.

DESIGN FOR STOVE.

Specification forming part of Design No. 7,814, dated November 3, 1874; application filed October 15, 1874.
[Term of Patent 14 years.]

To all whom it may concern:

Be it known that I, WILLIAM P. ABENDROTH, of the town of Port Chester, in the county of Westchester and State of New York, have invented a Design for a Stove, of which the following is a specification:

The nature of my design is fully represented in the annexed drawing or illustration made by a print from a wood-cut, as shown at A.

The general configuration of the design is that of a parallelopiped, or figure whose sides are parallelograms, and at the front lower edge is a horizontal projection which serves the purpose of an ash-receptacle, and which projects forward to a sufficient degree to support the fender and hearth.

The top plate of the stove proper is raised like an inverted tray, and is perforated as represented at D and E. Upon the center thereof may be placed a vase for holding water, as shown at F.

The front plate is also ornamented around the arch over the grate by a rose and its stem

or some leaves, and also a sprig of fuschia, as shown, and also a key-stone of scroll-work in the center of the arch.

The opposite sides of said plate are furnished with a column, and above each column, on the top plate, are placed knobs like acorns, which may be highly polished.

The panels on each side are provided with raised figures, that may also be easily polished by smoothing their raised surfaces, the groundwork being stippled or blistered in the casting.

What I claim as my invention is—

A design for a stove in the form of a parallelopiped, with a projecting base for the ash-chamber, and with a raised and perforated top plate, and with panels and polished raised ornaments, substantially as described.

WILLIAM P. ABENDROTH.
